United States Patent Office

Des. 209,924
Patented Jan. 16, 1968

209,924

GUITAR BODY OR SIMILAR ARTICLE

Charles H. Kaman, Simsbury, Conn., assignor to Kaman Aircraft Corporation, Bloomfield, Conn., a corporation of Connecticut

Continuation-in-part of design application Ser. No. 3,174, July 21, 1966. This application Jan. 27, 1967, Ser. No. 5,583

Term of patent 14 years

(Cl. D56—1)

FIG. 2

FIG. 1

FIG. 6

FIG. 5

FIG. 4

FIG. 3

FIG. 1

FIG. 1 is a plan view of a guitar body or similar article showing my new design.

FIG. 2 is a side view thereof.

FIG. 3 is a rear view thereof.

FIG. 4 is a transverse cross-sectional view thereof taken on the line 4—4 of FIG. 1.

FIG. 5 is a transverse cross-sectional view thereof taken on the line 5—5 of FIG. 1.

FIG. 6 is a transverse cross-sectional view thereof taken on the line 6—6 of FIG. 1.

FIG. 7 is a perspective view thereof showing generally its rear and one side.

This application is a continuation-in-part of my co-pending companion application Ser. No. D. 3,174, filed July 21, 1966, now abandoned.

I claim:

The ornamental design for a guitar body or similar article, as shown and described.
